UNITED STATES PATENT OFFICE.

EDGAR H. CLARK, OF AUSTIN, ILLINOIS, ASSIGNOR, BY DIRECT AND MESNE ASSIGNMENTS, TO WESTERN ELECTRIC COMPANY, OF NEW YORK, N. Y., A CORPORATION OF ILLINOIS.

AUTOMATIC SWITCHING SYSTEM.

1,125,965,

Specification of Letters Patent.

Patented Jan. 26, 1915.

Application filed January 20, 1908. Serial No. 411,669.

To all whom it may concern:

Be it known that I, EDGAR H. CLARK, a citizen of the United States of America, and a resident of Austin, county of Cook, 5 and State of Illinois, have invented a new and useful Improvement in Automatic Switching Systems, of which the following is a specification.

My invention pertains to switch systems 10 suitable for telephone exchanges and its ultimate object is the economy of line conductors.

It relates particularly to telephone systems wherein one or more main offices are 15 supplemented by one or more outlying offices, or "sub-offices," in which groups of subscribers' lines center and between which and the main office or offices trunk lines extend.

20 I have chosen particularly to illustrate my invention as applied to a telephone system employing manually operated switchboards at its main switching center or centers, but obviously it may be applied to 25 other than manual systems.

In connection with a manual switchboard I provide an outlying distribution point from which I cause to radiate short subscriber's lines. On the manual switchboard 30 at the main or central office I provide calling and answering jacks and line signals, in short, a complete manual switchboard line equipment at the central office for each of the subscriber's lines radiating from the 35 outlying distribution point. Between the outlying distribution point and the manual switchboard I provide a system of automatically operating trunk circuits and switches, the trunks being fewer in number 40 than the number of subscriber's lines radiating from the outlying distribution point and the operation of the switches being such that, when the switching conditions of the telephone exchange as a whole require 45 that any one of the outlying radiating subscriber's lines be connected through a trunk circuit with its set of switchboard apparatus, that connection is made and maintained automatically by the trunk circuits 50 and apparatus, and is automatically disconnected when the necessity for its maintenance no longer exists.

In the drawings, trunks are shown of two classes, first for connecting a calling line

with its switchboard equipment and second 55 for connecting a calling switchboard equipment with its line.

In the drawings, Figure 1 shows the circuits of a manual switch plug for use with the automatic trunk of my invention; Fig. 60 2 shows circuits of the central office equipment of a subscriber's line; and circuits of the central office end of a trunk which connects a calling subscriber's line to its corresponding line equipment upon the manual 65 switchboard; Fig. 3 shows a subscriber's line extending from an outlying distribution point; and the circuits of the alternative end of the trunk of Fig. 2; Fig. 4 shows the circuits of the central office line equipment 70 shown in Fig. 2; and the circuits of the central office end of a trunk which connects a central office line equipment to its corresponding subscriber's line extending 75 from the outlying distribution point, when a plug is inserted in a switchboard jack of the line equipment; Fig. 5 shows the circuits of the subscriber's line shown in Fig. 3; and the circuits of the alternative end of the trunk of Fig. 4; Figs. 6, 7 and 8 show 80 mechanical details of the automatic switches in which the trunk circuits terminate both at the central office and at the outlying distribution point, Fig. 6 being a general figure, Fig. 7 a view of the off-normal switch 85 in the direction of the arrow M, and Fig. 8 being view of wiper 12 and springs 20, section of wiper shaft 6 being taken on the line N—N in the direction shown by the arrow N.

In Fig. 6 are shown details of an automatic switch similar in most details to the well-known Strowger switch. The detent pawl is normally cut out of contact with the ratchet 2 and rack 3; when the release relay 4 is energized, detent pawl 1 is permitted to drop into contact with ratchet 2 and rack 3. Successive energizations of vertical magnet 5 lift wiper shaft 6, and successive energizations of rotary magnet 7 rotate wiper shaft 6. Wipers 8, 9, 10, 11 100 are of the usual type of wiper for making connections with contact pieces in a bank of contacts. Wiper 12 is a fixed collar adjacent to pairs of contact springs 21, 22, 23, 24, 25, etc. These pairs of springs are separated vertically by the distance of one vertical step of the wiper shaft 6; wiper 12 passes the pairs of springs in order and 105

presses one pair and only one pair into contact when in any one of its positions except the normal position of rest, in which position it is shown in the drawing. The off-normal switch 13-14-15 has its spring 14 held against its spring 15 by leaf 16 on wiper shaft 6, the spring 14 being released at the first rotary step of wiper shaft 6.

Figs. 2 and 3 together show a complete circuit of a trunk for connecting a calling line to its switchboard equipment. The operation is as follows: Assume that substation 56 calls, removing the receiver from the hook, thus closing the line circuit, and assume that the directory number of this substation is "56" or "156," or some directory number in which "56" identifies the position of the substation 56 in a group and the remaining portions of the directory number identify the group. Upon the closing of the circuit of the line at substation 56, current flows from battery B' through 17^L, 19, 56, 18, 17^H, energizing subscriber's primary line relay 17 and closing path for current through B', subscriber's secondary line relay 30^H, and resistance 31, energizing relay 30^H. Relay 30^H closes path for current through B'', release relay 4^a, 4', 4'', 80, 81^a, 82^a, 83, 33, 34', 35, 30', earth, energizing release relay 4^a, by the closure of whose armature 4^a path is closed for current through B³, release relay 4^a, 77 and earth. By closure of armature 4^a, contact spring 4' is broken from contact 4'' and connected to 4^a thereby providing a path for continuing the energization of 4^a independently of the off-normal switch 81^a-82^a. Relay 30^H also closes a path for pulsations of current through B'', interrupter I, 32', vertical magnet 5^a of the automatic switch of Fig. 3 (corresponding to 5 of Fig. 6), 33, 34', 35, 30', earth, and by each pulsation vertical magnet 5^a is energized, lifting the wiper shaft 6^a one step; 5^a also closes its electrical armature contact and completes path for current through B³, 5^a, 36, 15^a, 14^a, 37, 38, 39, earth, thereby (by the energization of vertical magnet 5^a of the automatic switch in Fig. 2) stepping the wiper shaft 6^a of Fig. 2 up the number of steps equal to the steps taken by the wiper shaft 6^a; thus the wiper shafts 6^a and 6^A belonging to the two ends of the same trunk, which may be designated trunk A, containing conductors 38 and 46, move vertically substantially in unison. The step-by-step movement of the shaft 6 moves the wiper 12^a over the springs 21^a, etc., until the fifth pair of springs 25^a (corresponding to the first digit of the directory number of the substation 56) is closed, when a path is formed for current through B'', 40, 32^a, 32'', 41, 25^a, 42, 30', earth, energizing the first pilot switch or relay 32^a; the relay 32^a, by its armature 32', interrupts the pulsating circuit above traced through vertical magnet 5^a; by

its armature 32^a, it locks itself over the path B'', 40, 32^a, 32'', 32^a, 43, 4^a, earth; by its armature 32^a, it closes path for pulsations of current through B'', I, 44, 34'', rotary magnet 7^a, 32^a, 33, 34', 35, 30', earth, and by each pulsation rotary magnet 7^a is energized, rotating the wiper shaft 6^a one step; 7^a also closes its electrical armature contact and completes path for current through B³, 7^a, 45', 46, 47, earth, thereby (by the combination of rotary magnet 7^a of the switch of Fig. 2) stepping the wiper shaft 6^A around the number of steps equal to the number of steps taken by the wiper shaft 6^a; thus the wiper shafts 6^a and 6^A, belonging to the two ends of the trunk A, move in rotary motion substantially in unison. The step-by-step rotary movement of the shaft 6^A moves the wiper 11^a over the contact pieces of the fifth level of contacts in the contact bank of the switch until contact piece 56^a (corresponding to the second digit of the directory number of the substation 56) is reached, when path is completed for current through B'', 40, 34^a, 34', 11^a, 56^a, 49, 30', earth, energizing the second pilot switch or relay 34^a; the relay 34^a, by its armature 34'', interrupts the pulsating current above traced through rotary magnet 7^a; by its armature 34^a, it locks itself over the circuit B'', 40, 34^a, 34^b, 34^a, 84, 4^a, earth; by its armature 34^a, it switches conductor 35 from conductor 33 to conductor 51^a, the import of which will be discussed later; by its armature 34^b, it completes path for current through B'', 40, home trunk-extension relay 53^a, 54, 34^b, 52, earth, energizing relay 53^a and holding it energized; by movement of its armature 34^b, 34^a has been broken from 34^b, and 34^a has made contact with 34^b, thus connecting the winding of relay 4^a to wiper 10^a, through 4^a, 4'', 4^a, 33, 34^a, 34^b, 10^a, thence to 56^a, 50, 31, and earth. Batteries B' and B'' are equal or are one battery; by the connection of the low resistance relay 4^a to resistance 31, the high-resistance secondary line relay 30^H is shunted out and releases its armature 30'; this removes the earth connection from conductor 35, which is common to all lines of the group to which substation 56 belongs, and from conductor 41, which is common to all lines on the fifth level of the bank of contacts of the automatic switch of Fig. 3. The switching of conductor 35 from conductor 33 to conductor 51^a is for the following purpose:—The operating magnets 4^a, 5^a and 7^a of the switch of the trunk A are normally connected to the conductor 33, and, when the trunk A is idle, are connected through armature 34^a to conductor 35; when the trunk A is busy (as is now considered to be the case because of the calling of substation 56), the armature 34^a disconnects those operating magnets and extends the 125

common conductor 35 through conductor 51^a to the armature corresponding to the armature 34' in the second pilot relay 34^b of trunk B, where it is connected to conductor 33^b, and thus to the operating magnets of the automatic switch of trunk B, so that trunk B may receive and respond to the next call originating in the group to which substation 56 belongs, and when trunk B 10 has responded properly to the second call from the group, trunk A remaining busy, the operation of pilot relay 34^b will extend common conductor 35 through conductor 51^b to the operating magnets of trunk C, 15 and so on throughout all trunks of the group of trunks serving the group of lines. By the first rotary step of wiper shaft 6^a, switch spring 14^a was released, breaking contact from spring 15^a and making contact with spring 13^a. By energization of 20 home trunk-extension relay 53^a, the trunk conductors are extended to the calling substation, and path is closed for current through B', 17^L, 56', 8^a, contact of 53^a, 38, 25 37, 14^A, 13^A, 55, contacts of relay 45^A, helix of 45^A, earth, retaining the energization of relay 17 and energizing distant trunk-extension relay 45^A, which then locks itself 30 through B^a, contact of 4^A, 57, resistance 58, 45'', 45^A, earth. By the energization of relay 45^A, the trunk conductors are extended to the line jacks corresponding to the calling substation and path is closed for current 35 through battery B⁴, line-signal-relay 56^a, 60', 61, 56^a, 9^a, 62, 45', 46, contact of 53^A, 9^a, 56'', 18, 56, 19, 56', 8^a, contact of 53^a, 38, 40 contact of 45^A, 63, 8^A, 56^b, 64, 65, 60'', earth, energizing relay 56^a, and resulting in the glowing of line lamp L. A branch circuit exists from conductor 18 through winding 17^H, but the resistance of winding 17^H shall be high enough to render its current negligible, 12,000 ohms being the resistance commonly used under such circumstances. In 45 response to the lighting of the line lamp L, the operator in charge inserts the plug P into the jack J, thus completing a talking circuit through B⁶, repeating coil winding 66, supervisory relay 67, 68, P, J, 61, 56^a, 50 9^a, 62, 45', 46, contact of 53^a, 9^a, 56'', 18, 56, 19, 56', 8^a, contact of 53^a, 38, contact of 45^A, 63, 8^A, 56^b, 64, J, P, 69, repeating coil winding 70. The subscriber's hook switch controls the supervisory relay 67 in the usual 55 manner. By the insertion of the plug P, path is completed also for current through B⁵, 71, 72, 73, 74, J, 60, earth, energizing cut-off relay 60 and extinguishing lamp L in the usual manner. The energization of relay 60 connects earth to the resistance 75 in series with relay 56^a and the battery B⁴, but relay 56^a is not energized because of the path existing from battery B³ directly to the resistance 75, through armature 45^b, 76, 60 10^A, 56^b, to 75; as the batteries are the same

or similar, the relay 56^a has no potential difference at its terminals. The call is completed by the telephone operator in the usual manner. This completes the operation of setting up of a connection for a call 70 originating at substation 56, or any substation served by a trunk such as A. It may be noted that the connection through the trunk A thus set up is not under the control of the originating substation, that substation controlling only the supervisory relay 67 and lamp 74. All the energized relays of the trunk A are held energized through the armature 17', or through contacts which ultimately are held through armature 17', but 75 armature 17' is not under control of the substation 56 so long as plug P is in jack J, because of the circuit B', 17^L, 56', 8^a, contact of 53^a, 38, contact of 45^A, 63, 8^A, 56^b, 64, J, P, 69, 70, earth. Therefore, after the hanging up of the receiver at substation 56, the trunk A is held by the plug P until disconnection by the operator. 80

In disconnecting, when the circuit is broken at the substation and the operator's plug has been removed, the relay 17 is de-energized; the armature 17' then releases the relay 4^a, whose armature then releases relay 4^A. By the release of relays 4^a and 4^A, all circuits and mechanisms are permitted to be restored to the normal condition of idleness, such restoration being completed by the final closing of the off-normal switch 81^a—82^a. The final step of restoration thus closes the circuit of 4^a through 80 and 83, which is the first circuit used in the normal operation of the device; thus complete mechanical restoration is compelled before the device may begin its response to the next succeeding call. 95

Trunks per Figs. 2-3 and Figs. 4-5 may be equipped with switches such as shown in Fig. 6, the springs 21, etc., of the switches of Figs. 2 and 5 being unconnected or omitted, and the switch 13-14-15 of the switches 100 of Figs. 3 and 4 being unconnected or omitted. The trunks are of two classes,—the first class for connecting an outlying subscriber's line to its switchboard line equipment when a substation originates a call, 110 and the second class for connecting a switchboard line equipment to its outlying subscriber's line when a call for the substation is originated elsewhere. A trunk of the first class is shown in Figs. 2-3 and has 115 been described above. A trunk of the second class is shown in Figs. 4-5. The central office line equipment of the line or substation 56 is shown in Fig. 2 and also in Fig. 4, while the subscriber's line and substation 120 56 and its primary and secondary line relays 17 and 30^H are shown in Fig. 3 and also in Fig. 5. 125

The operation of a trunk of the second class, as shown in Figs. 4-5, is as follows: 130

Assume that a call has originated upon the switchboard for the substation 56. The operator in charge of the plug P of Fig. 1, desiring to connect with the substation 56 by means of the plug P, inserts the plug P into the jack J or into any of the multiple jacks of the switchboard line equipment, and the following automatic action takes place: Upon the insertion of the plug P, current flows through B⁸, 71, 72, 73, 74, P, J, 60, earth, energizing the cut-off relay 60 which, by its armature 60'', closes path for current through battery B⁴, secondary switchboard relay 56⁹, resistance 75, 60'', earth, energizing the secondary switchboard relay 56⁹ and attracting its armature 130'. Relay 56⁹ closes path for current through B⁸, release relay 4^R, 104', 104'', 180, 81^R, 82^R, 183, 133, 134', 135, 130', earth, energizing release relay 4^R, by the closing of whose armature 104' path is closed for current through B⁸, release relay 4', 177 and earth. By closure of armature 104', contact spring 104' is broken from contact 104' and connected to 104'', thereby providing path for continuing the energization of 4^A independently of the off-normal switch 81^R—82^R. Relay 56⁹ also closes a path for pulsations of current through B⁸, interrupter I', 132', vertical magnet 5^R of the automatic switch of Fig. 4 (corresponding to 5 of Fig. 6) 133, 134', 135, 130', earth, and by each pulsation vertical magnet 5^R is energized lifting the wiper shaft 6^R one step; 5^R also closes its electrical armature contact and completes path for current through B⁸, 5^R, 136, 15^R, 14^R, 137, 138, 139, earth, thereby (by the energization of vertical magnet 5^R of the automatic switch of Fig. 5) stepping the wiper shaft 6^R of Fig. 5 up the number of steps equal to the steps taken by the wiper shaft 6^R; thus the wiper shafts 6^R and 6^R belonging to the two ends of the same trunk, which may be designated trunk R, containing conductors 138 and 146, move vertically, substantially in unison. The step-by-step movement of the shaft 6^R moves the wiper 12^R over the springs 21^R, etc. until the fifth pair of springs 25^R (corresponding to the first digit of the directory number of the desired line) is closed, when a path is formed for current through B⁸, 140, 32^R, 132'', 141, 25^R, 142, 130', earth, energizing the first pilot switch or relay 32^R; relay 32^R, by its armature 132', interrupts the pulsating circuit above traced through vertical magnet 5^R; by its armature 132'', it locks itself over the path B⁸, 140, 32^R, 132'', 132^R, 143, contact, 104', earth; by its armature 132^R it closes path for pulsations of current through B⁸, I', 144, 134'', rotary magnet 7^R, 132^R, 133, 134', 135, 130', earth, and by each pulsation rotary magnet 7^R is energized, rotating the wiper shaft 6^R one step; 7^R also closes its

electrical armature contact and completes path for current through B⁸, 7^R, 145', 146, 147, earth, thereby (by the energizations of rotary magnet 7^R of the switch of Fig. 5) stepping the wiper shaft 6^R around the number of steps equal to the steps taken by the wiper shaft 6^R; thus the wiper shafts 6^R and 6^R belonging to the two ends of the trunk R move in rotary motion substantially in unison. 75

The step-by-step rotary movement of the shaft 6^R moves the wiper 11^R over the contact pieces of the fifth level of contacts in the contact bank of the switch until contact piece 156^R (corresponding to the second digit of the directory number of the line desired) is reached, when path is completed for current through B⁸, 140, 34^R, 134^R, 11^R, 156^R, 149, 130', earth, energizing the second pilot switch or relay 34^R; the relay 34^R, by its armature 134'', interrupts the pulsating circuit path traced through the rotary magnet 7^R; by its armature 134', it locks itself over the circuit B⁸, 140, 34^R, 134^R, 134', 184, 104', earth; by its armature 134' it switches conductor 135 from conductor 133 to conductor 51^R, the import of which will be discussed later; by its armature 134'', it completes path for current through B⁸, 140, home trunk-extension relay 53^R, 154, 134^R, 152, earth; energizing relay 53^R and holding it energized; by movement of its armature 134', 134' has been broken from 134^R and 134^R has made contact with 134', thus connecting the winding of relay 4^R to wiper 10^R, through 4^R, 104', 104^R, 133, 134^R, 134', 10^R, thence to 156^R, 150, 75, 60' and earth. Batteries B⁸ and B⁴ are equal or are one battery; by the connection of the low-resistance relay 34^R to the resistance 75, the high-resistance secondary switchboard relay 56⁹ is shunted out and releases its armature 130'; this removes the earth connection from conductor 135 which is common to all switchboard line equipments of the group to which the desired line (56) belongs, and from conductor 141, which is common to all switchboard line equipments on the fifth level of the bank of contacts of the automatic switch of Fig. 4. 105

The switching of conductor 135 from conductor 133 to conductor 51^R is for the purpose of transferring the next call originating on the switchboard and for this group of lines to be cared for by the operating magnets of the trunk S to which second pilot relay 34^R belongs; the relay 34^R in turn transferring subsequent calls further by extending the conductor 135 to the conductor 51^R when the trunk S is busy. By the first rotary step of wiper shaft 6^R, switch spring 14^R was released, breaking contact from spring 15^R and making contact with spring 13^R. By the energization of home trunk-extension relay 53^R, the trunk con- 110

ductors are extended to the connecting plug P and path is closed for current through B'', 45^r, 145'', 155, 13^r, 14^r, 137, 138, contact of 53^R, 8^R, 156'', 199, J, P, 69, 70, earth, 5 energizing distant trunk-extension relay 45^r, which then locks itself through B'', 45^r, 145'', resistance 158, contact of 4^r and earth. By the energization of relay 45^r the trunk conductors are extended to the line conductors 18 and 19 of the line desired, viz., that line leading to substation 56. Considering that the line circuit is open at the hook switch of substation 56, the only circuit through the supervisory relay 67 is B^s, 66, 15, 67, 68, P, J, 161, 156'', 9^R, contact of 53^R, 146, contact of 45^r, 9^r, 156^s, 17^H, earth, but inasmuch as the resistance of 17^H is high, say 12,000 ohms, the supervisory relay 67 does not respond to the current. The supervisory relay 67 is under control of the hook switch of the substation 56 since when that switch is closed the circuit will exist through B^s, 66, 67, 68, P, J, 161, 156'', 9^R, contact of 53^R, 146, contact of 45^r, 9^r, 156^s. 25 19, 56, 18, 156^s, 8^r, contact of 45^r, 138, contact of 53^R, 8^R, 156'', 199, J, P, 69, 70. Upon the closing of the home and distant trunk-extension relays path is closed for current through B', 17^L, 156^s, 8^r, contact of 45^r, 138, 30 contact of 53^R, 8^R, 156'', 199, J, P, 69, 70, earth, energizing relay 17. The closing of armature 17 effects nothing. Current flows through 31 but not through 30^H since one terminal of 30^H is connected directly to battery B' and the other terminal is connected through 198, 197, 156^s, 10^r, contact of 45^r to battery B'', these two batteries being the same or similar. The operator, having plugged into the jack J (the above outlined 35 40 automatic action having followed quickly), now rings by the operation of the ringing key K. While this key is operated the relay 17 is held energized by current through B', 17^L, 156^s, 8^r, contact of 45^r, 138, contact of 53^R, 8^R, 156'', 199, J, P, 196, earth, and ringing current flows from generator G through 195, 68, P, J, 161, 156'', 9^R, contact of 53^R, 146, contact of 45^r, 9^r, 156^s, condenser and ringer of 56, 156^s, 8^r, contact of 50 45^r, 138, contact of 53^R, 8^R, 156'', 199, J, P, 69, 196.

In disconnection, the trunk is released by removal of the operator's plug P regardless of the open or closed condition of the hook switch of substation 56. By withdrawal of the plug P, the circuit through relay 60 is broken; by the release of armature 60^H the circuit through relay 4^R is broken; by the release of armature 104^R the circuit through 55 release relay 4^r is broken. Thus all parts are restored to their normal condition of idleness, the final step being the closure of off-normal switch 81^R—82^R, as described in connection with the corresponding switch 60 of Fig. 3.

By restoration of the automatic switch of Fig. 5 the shunt is removed from 30^H, and if at such a time the subscriber at substation 56 has his receiver off the hook, relays 17 and 30^H will be energized and a call will be 70 forwarded to the lamp 195 by some trunk of the first class, as trunk A.

I have described a telephone system in which a switchboard operates in connection with outlying subscriber's lines through 75 trunks equipped with automatic switches at each end, the two switches of the two ends of the trunk operating in unison to connect any outlying line with its switchboard line equipment or vice versa. 80

It will be noted that the paths, which normally lead from the subscribers' jacks or connection terminals at the main switchboard, terminate in open contacts on the automatic switches which are normally connected to nothing else. In this respect these paths may be called blind paths, in the sense, for instance, that an alley which comes to an abrupt end, and leads nowhere, is a blind alley. Similarly, the branches 85 from the subscribers' lines at the sub-office, which lead from the line conductors to the contacts on the switches, are blind paths leading from the subscribers' lines, since normally there is no path beyond. With 90 this in view, the following statement will make clear one of the fundamental features of my invention. The jacks or connection terminals at the main office, although each of them corresponds definitely to a 95 given subscriber's line, normally are wholly dissociated from the subscribers' lines, except in so far as they may bear the same designating numbers or other insignia. The paths leading from these jacks are normally 100 blind paths. The subscribers' lines which terminate at the sub-station each has a branch path leading to contacts in the automatic switches, from which contacts there is no normal path, and these branches therefore, are blind paths. Each of these contacts and each of these blind paths is normally physically dissociated from its corresponding jack or other connection terminal on the distant central office switchboard, the 105 only association being that they bear corresponding numbers or other insignia. The trunks from the main office to the branch office, or sub-office, are fewer in number than the corresponding group of lines at the sub-office and fewer in number than the corresponding group of jacks or other connection terminals at the main office; and these trunks have for their function the connecting together, as required, of any one of the 110 blind paths leading from the switchboard terminals to the corresponding one of the blind paths leading from the subscribers' lines. Each of these trunks has a switching mechanism at each end, the two switching 115 120 125 130

mechanisms of each trunk being so arranged that when one of them moves to connect that trunk with the blind path of a certain number at one end, the other will simultaneously move to connect with the blind path bearing the same number at the other end. Thus, in the case of a manual switchboard, when the operator at the main office receives a call for a certain line in the sub-office, she plugs into the jack corresponding to the line wanted, in spite of the fact that at the time that jack terminates in a blind path which has no association with the line wanted, except that it bears the same number. The automatic switching apparatus associated with the two ends of the first idle trunk then, in response to this act, automatically connects one end of the trunk with the blind path chosen by the operator, and the other end of the trunk with the blind path leading from the desired subscriber's line. Similarly, with respect to a call originating on one of the sub-office lines, the removal of the subscriber's receiver from its hook in making a call will establish such a condition that the first idle trunk will connect with the normally blind path from the calling subscriber's line, and at the same time the switching mechanism at the other end of this line will automatically connect the other end of that trunk to the normally blind path leading from the jack which bears the corresponding subscriber's number. In either case the trunk automatically supplies the connecting link between the two physically dissociated blind paths, and thus supplies the physical associating link between the line and its connection terminal on the switchboard where the only previously existing association had been that of number or other corresponding designation.

I believe myself to be the first to have devised a system having this broad method of operation, by which the connecting links between a line and its correspondingly designated switchboard terminal are normally missing, the line and its switchboard terminal being associated only by number or other corresponding insignia, and by which the connecting physical link is automatically supplied only at the time of the required connection.

Obviously, a system operating in this way is capable of use with a wide variety of telephone switching systems, and is in itself susceptible to wide variation without departure from the spirit of the broad invention as I have outlined it. In some of the claims which follow I have used the term "blind path" in accordance with the meaning just defined.

Having thus described my invention, what I claim as new and desire to secure by United States Letters Patent is;

1. In a telephone system, a switchboard having a plurality of subscriber's-line equipments; a plurality of subscribers' lines dissociated from said switchboard, and pertaining one to each of said line equipments; and a trunk common to all subscribers' lines and having ends equipped with switches acting automatically to connect one of said subscriber's lines to its corresponding line equipment when controlled initially by one of said subscriber's-line equipments, substantially as described. 75

2. In a telephone system, a switchboard having a plurality of subscriber's-line equipments; a plurality of subscribers' lines dissociated from said switchboard, and pertaining one to each of said line equipments; and a trunk having automatic connectors at each end whereby any subscriber's line may be connected through the trunk and its automatic switches to that subscriber's line's switchboard equipment, substantially as described. 80 85

3. In a telephone system, a trunk line; two selecting switches, one for each end of said trunk line; stationary contacts at said switches; and electromagnetic means for automatically moving said two switches in unison to unite with corresponding contacts, substantially as described. 90 95

4. In a telephone system, a switchboard having a plurality of subscriber's-line equipments; a plurality of subscribers' lines dissociated from said switchboard, and pertaining one to each of said line equipments; an automatic switch for selecting and connecting with said subscriber's lines; an automatic switch for selecting and connecting with said subscriber's line equipments of said switchboard; and means for causing 100 105 said two automatic switches to move in corresponding steps, substantially as described.

5. In a telephone system, a switchboard having a plurality of subscriber's-line equipments; a plurality of subscribers' lines dissociated from said switchboard, and pertaining one to each of said line equipments; an automatic switch for selecting and connecting with said subscriber's lines; an automatic switch for selecting and connecting 110 115 with said subscriber's line equipments of said switchboard; and electrical armature contacts on the operating magnets of one of said automatic switches and controlling the circuits of the operating magnets of the 120 other of said switches, substantially as described.

6. In a telephone system, a switchboard having a plurality of subscriber's-line equipments; a plurality of subscribers' lines dissociated from said switchboard, and pertaining one to each of said line equipments; trunks between said switchboard equipment and said lines; means controlled by one of said lines for causing one of said trunks 125 130

to connect with said line, and further means for causing the alternative end of said trunk to connect automatically with that subscriber's-line equipment of the switchboard which pertains to said subscriber's-line, substantially as described.

7. In a telephone system, a plurality of outlying subscribers' lines; a manual switchboard; jacks and plugs on said switchboard, said jacks corresponding severally to the respective subscribers' lines; a trunk; means controlled by the insertion of a plug in a jack to cause the connection of said trunk with said jack; and further means for connecting automatically the other end of said trunk with the corresponding outlying subscriber's line, substantially as described.

8. In a telephone system, an automatic switch, said automatic switch having an operating magnet and a normally closed off-normal switch; an operating circuit including said operating magnet and said off-normal switch in series, whereby the first energization of said operating magnet may be had only through said off-normal switch; an auxiliary operating circuit; means for making said auxiliary circuit effective only through said first operating circuit; and means for interrupting said auxiliary in the beginning of the process of disconnection and restoration.

9. In a telephone system, an automatic switch; an operating circuit for said automatic switch whereby said switch may be actuated selectively: a main controlling circuit for said switch; a self-locking relay holding said main controlling circuit normally open when said switch is in its position of idleness; and a primary circuit for energizing said relay to close said main controlling circuit and including the normally-closed contacts of an off-normal switch.

10. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; and circuits adapted to maintain said automatic switches in analogous positions.

11. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; a means of control rendered active by any of said lines and acting to cause the

switch contiguous to the lines to connect the trunk with the controlling line; and further means for moving said switches in unison.

12. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; a means of control rendered active by any of said lines and acting to cause the switch contiguous to the lines to connect the trunk with the controlling line, and further means for causing the other of said switches to take a selective position analogous to the first switch controlled.

13. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said switches moving in unison.

14. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said switches being controlled one by the other in their movements of selection.

15. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said switches being controlled independently one by the other, whereby both are caused to occupy analogous positions of selection.

16. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said switches being independently controlled one by the other, the controlling magnets of one being included in circuits

over the trunk conductors to controlling relay contacts of the other during the progress of selective movement.

17. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said two automatic switches moving at all times in corresponding steps.
18. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said two automatic switches moving at all times in corresponding steps, and said lines and jacks being identifiable in related pairs comprising each a line and a jack by the analogous positions of the line and the jack.
19. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; said two automatic switches moving at all times in corresponding steps, said lines and jacks being related in pairs and analogously located in said selecting switches, and whereby in all effective positions of selection, said two automatic switches connect a jack to its corresponding line.
20. In a telephone system, a switchboard having a plurality of line jacks; a plurality of lines normally disconnected from said line jacks and pertaining one to each of said line jacks; a pair of automatic switches, and a trunk connecting them, the automatic switch at one end being adapted to connect with any line, and the automatic switch at the other end being adapted to connect with any jack; switch plugs for said jacks, means for operating the automatic switch contiguous to said jacks in response to the insertion of a plug in a jack and to connect the trunk to the jack plugged into, and further means for moving the two automatic switches in unison.
21. In a telephone system, a switchboard having a plurality of line jacks; a plurality of lines normally disconnected from said

line jacks and pertaining one to each of said line jacks; a pair of automatic switches, and a trunk connecting them, the automatic switch at one end being adapted to connect with any line, and the automatic switch at the other end being adapted to connect with any jack; switch plugs for said jacks, means for operating the automatic switch contiguous to said jacks in response to the insertion of a plug in a jack and to connect the trunk to the jack plugged into, and further means for effecting analogous positions of selection in said two switches automatically.

22. In a telephone system, a main office and a sub-office; automatic switching apparatus at both said offices; a group of subscribers' lines terminating at said sub-office; a normally blind path from each subscriber's line to said sub-office switching apparatus; switchboard connection terminals, one for each subscriber's line at said main office; a normally blind path leading from each of said connection terminals at the main office; a group of trunk lines connecting said offices, fewer in number than the blind paths of the corresponding groups at said main office and at said sub-office, and means for automatically causing the switching apparatus to connect the two ends of one trunk to the corresponding blind paths pertaining to a given subscriber's line upon the origination of a call.

23. In a telephone system, a main office and a sub-office; automatic trunk switching apparatus at both said offices; a group of subscribers' lines terminating at said sub-office; a normally blind path from each subscriber's line to said sub-office switching apparatus; switchboard connection terminals, one for each subscriber's line at said main office; a normally blind path leading from each of said connection terminals at the main office; a group of trunk lines connecting said offices, fewer in number than the corresponding groups of blind paths at said main office and at said sub-office; means for automatically causing the main and sub-office switching apparatus to connect the two ends of one trunk to the corresponding blind paths pertaining to a given subscriber's line upon the origination of a call, and means for guarding said trunk and said blind paths from other connections during the existence of an established connection.

24. In a telephone system, a main office and a sub-office; switching apparatus at both said offices; a group of subscribers' lines terminating at said sub-office; a group of connection terminals at said main office, each connection terminal of said group pertaining to a corresponding individual line in said group of lines, but normally physically dissociated therefrom; a normally blind path from each subscriber's line to said sub-office switching apparatus; a nor-

5 mally blind path leading from each connection terminal at the main office; a group of trunks connecting said offices, fewer in number than the corresponding groups of connection terminals and lines, and means for 10 causing the main and sub-office switching apparatus automatically to connect one end of each trunk to the blind path of a line at the sub-office and the other end to the blind path of a corresponding connection terminal at the main office upon the origination of a call at one end of said trunk line.

15 25. In a telephone system, a trunk line; an automatic selecting switch at each end of said trunk line; a group of paths terminating in each of said switches, and means for automatically moving said two switches in unison to connect the two ends of said trunk line to corresponding ones of said 20 paths.

25 26. In a telephone system, a subscriber's line; a switchboard terminal individual to that line, but physically dissociated therefrom; a connecting link common to a group 30 of such lines and terminals, and automatic means responsive when a call is originated at one end of said connecting link for simultaneously applying the ends of said connecting link to said line and terminal.

30 27. In a telephone system, a group of subscribers' lines; a group of switchboard terminals dissociated therefrom; a group of incoming trunks; switches at each end of said trunks for automatically connecting a 35 subscriber's line to its corresponding switchboard terminal; another group of subscribers' lines; another group of switchboard terminals dissociated therefrom; an outgoing trunk; switches at each end of each 40 outgoing trunk for automatically connecting one of said lines to the corresponding one of said switchboard terminals, and means for establishing a connection between said switchboard terminal so connected for completing the circuit between 45 said subscribers' lines.

28. In a telephone system the combination 50 with subscribers' lines, and an interconnecting switchboard therefor having switchboard lines, one for each subscriber's line, of trunk lines external to said switchboard and less in number than the number 55 of the subscribers' lines, and automatic means responsive when any of said subscribers is calling for connecting said subscribers

er's line through an idle one of said trunk lines to its corresponding exchange line.

29. In a telephone system the combination with a group of subscribers' lines, and an interconnecting switchboard having 60 switchboard lines, one for each subscriber's line of the said group, of a trunk line external to said switchboard, and automatic means responsive when any of said subscribers is calling for connecting said subscriber's line through the said trunk line to its corresponding switchboard line.

65 30. In a multi-office telephone system the combination with a plurality of lines terminating at one office, an automatic line 70 finder at said office, a switch associated with one of said lines, and means responsive to the operation of said switch to start said line finder in search of said line, of a circuit between said offices, and means at the 75 other of said offices controlled over said circuit to measure the movement of said line finder.

75 31. In a telephone system, a circuit, a pair of remote switches having electrically associated traveling contacts included in series in said circuit, passive contacts for each switch, means for causing one of said switches to seek out and connect with a particular passive contact, means for causing the other switch to move in synchronism with the first switch to connect with a contact of the second switch corresponding to the connected contact of the first switch, whereby said circuit is extended through 80 corresponding passive contacts of each of said switches.

85 32. In a telephone system, a trunk line; two selecting switches, one for each end of said trunk line; contacts for said 90 switches, lines terminating in said contacts; and electromagnetic means actuated when a call is established on one of said lines for automatically moving said switches in unison to cause one switch to unite with the 95 terminals of the line upon which the call is established and the other switch to unite with the corresponding terminals thereof.

90 Signed by me at Chicago, county of Cook and State of Illinois, in the presence of two 100 witnesses.
